1 Claim. (Cl. 310—11)

It is a well known fact that magnetogasdynamic generators contain a duct through which flows an ionized gas, for example, a hot gas. When a magnetic field is generated perpendicularly to the direction of gas flow, a voltage is induced in the direction perpendicular to the direction of gas flow and perpendicular to the direction of the magnetic field. By means of appropriate electrodes, an electric current can be drawn off and conducted to an external load resistance in the form of electrical power.

Since the gases used as flow media are ionized only to a limited degree because their temperature must be kept within tolerance by the components of the generator, it becomes necessary to seed the gas with an additional material in order to increase its conductivity. This seed material has atoms which ionize easily, for example, caesium, potassium and calcium, and by supplying electrons causes an increase in the electrical conductivity of the gas. The gases of combustion of any fuel can be utilized as carrier gases; the air of combustion can be enriched by oxygen. After flowing through the generator duct, the flue gases are piped through a battery of heat-exchange devices to utilize the available heat, and thereupon they escape into the atmosphere.

If a closed cycle is employed, the costly seed material such as caesium can be re-used as often as desired by the return of the hot carrier gas which is mixed with the seed material to the cycle after it has flown through the generator duct and the heat-exchange devices, in other words it is re-heated and piped into the generator duct at the speed desired.

The proposal has been made to use rare gases such as argon, neon and helium as carrier gases for a magnetogasdodynamic generator with closed cycle because these gases have a low collision profile. The collision profile of a gas stream is defined as a value that is proportional to the probability of collisions of gas atoms with an electron. Since these collisions of gas atoms with the electrons reduce the mobility of the electrons within an electrical field, a high collision profile is synonymous to a low electrical conductivity. The collision profiles of the above mentioned rare gases are: argon 0.6×10^{-16} cm.², neon 1.1×10^{-16} cm.², helium 5.7×10^{-16} cm.².

The invention relates to a magnetogasdodynamic generator comprising a duct through which ionized gas flows, means to generate a magnetic field perpendicularly to the direction of gas flow, and two or more pairs of electrodes arranged perpendicularly to the magnetic field, where a hot carrier gas, seeded with substances to increase its conductivity, is circulated in a closed cycle, with a characteristic K-value assigned to said gas, said K-value comprising the molecular weight, the collision profile, the ratio of the specific heat to the gas constant, and a temperature coefficient. It is the invention that a carrier gas is utilized with a K-value which exceeds by at least 10% the corresponding K-value of helium.

The invention is the realization of the idea that the selection of the most appropriate carrier gas must not be based solely on its collision profile but on an over-all value which comprises, in addition to the collision profile, the molecular weight, and the specific heat of the gas as related to one mol.

Design and cost of a magnetogasdodynamic generator depend basically on the attainable power density which in turn is determined by the allowable ohmic losses. Maximum power density will be attained if the order of losses allowed is identical with the order of the power generated. However, in this case the magnitude of losses becomes intolerable and lower power densities must be accepted with the losses being limited to approximately 10 to 20% of the power generated. At a specified ratio of the ohmic losses to the power generated and a given magnetic field the power density is proportional to the electrical conductivity, and proportional to the second power of the velocity of flow of the gas.

The conductivity of a carrier gas, seeded with a substance in relatively low concentration, is approximately proportional to the following values:

The a -th power of the temperature where a is a function of seed material and temperature, its magnitude being close to the value 10;

20 The square root of the seed material concentration;
The reciprocal value of the square root of the pressure;
The reciprocal value of the collision profile of the carrier gas.

25 However, it is not possible to raise the electrical conductivity by increasing the concentration of the seed material at will because the collision profiles of the seeded molecules are usually much greater than the collision profiles of the carrier gases, and an increase in the concentration of the seed material would lead to an increase of the mean collision profile also. The most effective concentration of the seed material for maximum conductivity is approximately proportional to the collision profile of the carrier gas. If this most effective concentration of the seed material would be employed, the 30 conductivity ceases to be proportional to the reciprocal value of the collision profile of the carrier gas but will be proportional to the reciprocal value of the square root of the collision profile.

35 The velocity of flow within the duct is produced in a 40 nozzle by expansion of the gas from its state in the heating chamber. At the conversion from thermal to kinetic energy the velocity is increased while temperature and pressure are decreased. The conductivity of the gas will decrease also because the influence of the lower temperature is a preponderant factor. Therefore, there exists an optimum velocity for any given gas for maximum power density. This optimum velocity will depend on the specific heat of the gas as related to one mol. In case of carrier gases with low specific molar heat it is 45 below sonic velocity, and in case of carrier gases with high specific molar heat above the sonic velocity.

50 It was discovered that the power density of a magnetogasdodynamic generator with seed material added in at least approximate optimum concentration and at least 55 approximate optimum gas velocity becomes solely the function of characteristics of the carrier gas if specific values are established for the maximum value of the gas temperature at the entry into the generator duct and the exit from this duct as well as for the maximum value of the pressure. In this case the power density is inversely proportional to the molecular weight of the gas, inversely proportional to the square root of the collision profile of the gas, and increases monotonously with the ratio of specific heat to gas constant. A characteristic K-value 60 can be given for the carrier gas, with the power density of the generator being proportional to this K-value, and the interrelation found is expressed by the formula

$$70 K = \frac{1}{m\sqrt{Q}} \cdot \frac{4\lambda}{2a\lambda} \left[\frac{2a-\lambda}{2(a+1)-\lambda} \right]^{(a+1)-\frac{\lambda}{2}} \quad (1)$$

where:

m represents the molecular weight of the gas,
 Q the collision profile,
 λ the ratio of the specific heat to the gas constant, both
 in like units,
 a the exponent which expresses the conductivity of the
 gas mixed with the seed material in relation to the
 temperature.

Therefore, in order to attain a high power density it
 will be advantageous to select a carrier gas with a low
 molecular weight because the collision profile of such
 gas, although being higher per se, affects the character-
 10 istic K-value only by the reciprocal value of its square
 root but not by the reciprocal value as in case of the
 15 molecular weight.

However, the K-value depends also on λ , the ratio of
 the specific heat to the gas constant. For monatomic
 gases λ is constant, its value being 2.5. In case of di-
 atomic gases the λ value is 3.5 at room temperature and be-
 comes larger at higher temperatures. Polyatomic gases
 20 have a greater specific heat which increases with an in-
 crease in temperature, first because the energy of rotation
 and oscillation contributes to the specific heat, and sec-
 ondly, because the specific heat is increased greatly due
 25 to the dissociation into molecules of lower atomic num-
 ber. In case of the applicable gas temperature near
 2,300° K. the functional relation of λ , for values of λ
 up to =12, to the characteristic K-value is represented
 30 by the ascending branch of a parabola. Therefore,
 when a carrier gas is to be selected, next to the molecu-
 lar weight it is the influence of the specific heat and not
 the collision profile which is greatly more important for
 35 the power density. The invention makes it possible to
 find a carrier gas which is more advantageous than the
 gases proposed heretofore in that the characteristic K-
 value of the carrier gas exceeds by at least 10% the cor-
 responding K-value for helium.

Suitable is, for example, a light and dissociating gas
 40 where at the start of the dissociation the ratio of the
 specific heat to the gas constant is increased greatly and
 where at the same time the molecular weight m becomes
 smaller, whereby the magnitude of the characteristic
 K-value is increased.

A suitable light polyatomic gas is, for example, hydro-
 45 gen. If hydrogen is utilized as carrier gas, the power
 density of a magnetogasdynamic generator in which the
 carrier gas, mixed with seed material and circulated in a
 closed cycle, has a temperature of 2,250° K. will be
 50 proportional to a K-value of 4.51×10^{-2} , if $Q=10^{-16}$
 cm.^2 is used, while the corresponding figures for argon
 and helium being only 0.59×10^{-2} and 1.93×10^{-2} re-
 spectively. Therefore, it is the surprising result that the
 rare gases, heretofore proposed as carrier gases, are less
 55 advantageous than hydrogen even though their collision
 profile amounts only to $0.6 \times 10^{-16} \text{ cm.}^2$ and 5.7×10^{-16}
 cm.^2 compared to $14 \times 10^{-16} \text{ cm.}^2$ for hydrogen. This is
 due to the fact that at the temperature given, the ratio
 of the specific heat to the gas constant is 4.2 in case of
 60 hydrogen but 2.5 in case of argon and helium, and that
 the molecular weight of the hydrogen is only 2 compared
 with 40 for argon and 4 for helium.

A favorable power density can be obtained even if a
 gas mixture containing hydrogen is used as carrier gas,
 for example, a gas mixture of helium and hydrogen. In
 this case the various factors of the characteristic K-value:
 m (molecular weight), Q (collision profile) and λ (ratio
 of the specific heat to gas constant) must be averaged
 individually and substituted in the formula for K. It
 must be established in the form $\Sigma x_1 m_1$, $\Sigma x_1 Q_1$ and
 $\Sigma x_1 \lambda_1$ and substituted for m , Q and λ , where x_1 repre-
 65 sents the molar components of the individual gases in
 the mixture.

One suitable embodiment of a closed cycle type of
 magnetogasdynamic generator is shown in schematic form

in the attached drawing. Here it will be seen that the
 generator system includes a combustion chamber 1 which
 receives fuel such as, for example, coal from a container
 2. The fuel burned in the combustion chamber serves to
 5 heat compressed, seeded carrier gas admitted to chamber
 1 and to deliver the same at high velocity through the
 duct 3 of the generator. Associated with duct 3 is a
 magnetic field having a direction perpendicular to the
 direction of flow of the gas through the duct, this magnetic
 field being produced by a coil 5 wound upon a magnetic
 core located outside of the duct. Also associated with
 duct 3 is at least one pair of oppositely disposed electrodes
 10 4 which are located within the duct. As is well known,
 flow of the hot ionized carrier gas through duct 3 in the
 direction indicated by the arrow causes a direct voltage
 to be generated between the electrodes 4, and this voltage
 is applied to terminals 6 and can then be supplied in
 this form from these terminals to a load, or it can be
 converted into an alternating voltage if the load is of the
 latter type. The magnet coil 5 can also be supplied with
 its current from the terminals 5, as indicated in the draw-
 15 ing. The carrier gas after passing through the generator
 duct 3 is delivered to a heat exchanger 10 in which some
 of the heat energy remaining is extracted, and is then
 passed in heat exchange relationship through a steam
 20 boiler 9 which produces steam for driving a steam turbine
 8 which is connected by shafting to drive two axial flow
 type compressors 7 arranged in two stages. These
 25 compressors serve to re-compress the seeded carrier gas which
 is then delivered to and flows through the heat exchanger
 30 10 picking up some heat, and is then admitted once again
 to the combustion chamber 1 whereupon the cycle is then
 35 repeated. The operating cycle is thus a closed one since
 the seeded carrier gas is re-cycled continuously in a closed
 path from the combustion chamber 1 through duct 3,
 heat exchanger 10, steam boiler 9, axial flow compressors
 40 7 and back through heat exchanger 10 to the combustion
 chamber 1 for re-heating.

In accordance with the invention, the carrier gas utilized
 in the closed cycle has a K-value which exceeds, by at
 least 10%, the corresponding K-value for helium.

I claim:

In a magnetogasdynamic generator which includes a
 duct through which a hot ionized carrier gas seeded with
 45 a substance to increase its conductivity is caused to flow
 in a closed cycle, means establishing a magnetic field per-
 pendicularly to the path of gas flow in said duct, and at
 least one pair of spaced electrodes arranged in said duct
 50 perpendicularly to said magnetic field and also perpendicu-
 larly to the path of gas flow in said duct, the improve-
 ment wherein said carrier gas is constituted by a mixture
 of gases including hydrogen and has a K-value which
 exceeds by at least 10% the corresponding K-value for
 55 helium, said K-value being defined as

$$K = \frac{1}{m\sqrt{Q}} \cdot \frac{4\lambda}{2a-\lambda} \left[\frac{2a-\lambda}{2(a+1)-\lambda} \right]^{(a+1)-\frac{\lambda}{2}}$$

where:

m represents the molecular weight of the gas, Q the colli-
 sion profile, λ the ratio of the specific heat to the gas
 constant, both in like units, a the exponent which ex-
 60 presses the conductivity of the gas mixed with the seed
 material in relation to the temperature.

and determined by the molecular weight of the carrier
 gas, its collision profile, the ratio of the specific heat to
 the gas constant, and the temperature coefficient.
